ATTORNEY:

UNITED STATES PATENT OFFICE.

SAMUEL S. FISHER, OF ST. PAUL, MINNESOTA.

PEANUT HEATING AND DISPLAYING DEVICE.

Application filed December 18, 1922. Serial No. 607,741.

To all whom it may concern:

Be it known that I, SAMUEL S. FISHER, a citizen of the United States, residing at St. Paul, in the county of Ramsey and State 5 of Minnesota, have invented certain new and useful Improvements in Peanut Heating and Displaying Devices, of which the following is a specification.

My invention is a device particularly 10 designed for the use of storekeepers and for the purpose of storing, displaying and heating of roasted peanuts.

The object is to provide a device for 15 economically heating peanuts in a comparatively dry and air tight chamber and simultaneously displaying the peanuts and appropriate display signs forming an integral part of the device, both the heating and sign display being accomplished by the same 20 means, namely, electric lights, arranged as shown in the accompanying drawings, in which,—

Fig. 1 is a top view of the preferred form 25 of my device.

Fig. 2 is a front elevation of Fig. 1.

Fig. 3 is a right hand end elevation of 30 Fig. 2.

Fig. 4 is a sectional view as on line 4—4 in Fig. 2.

Fig. 5 is a sectional elevation about as on 35 line 5—5 in Fig. 4.

Fig. 6 is a perspective view of a simplified form of my device.

Fig. 7 is a detail of a glass panel used in 40 the lower compartment of my device.

Fig. 8 is a sectional view about as on line 8—8 in Fig. 6.

Referring to the drawings by reference 45 numerals, the preferred form of my device is an upright cabinet of rectangular form in horizontal section, the main frame 16 of which is made of any suitable wood or metal and preferably elevated on legs 9. In the preferred form of cabinet illustrated in

Figs. 1 to 5 inclusive, is a lower compartment 10 with a solid bottom 11 and a sheet metal top 12 with perforations 13, and an upper space extending from the floor 12 to the top of the cabinet, said upper space being divided by two vertical spaced partitions

14—15 into two compartments 10^a and 10^b (see Fig. 4) each of which has an open top closed by a lid 17 secured to the frame by

hinges 17^a.
55 In the front wall of the cabinet and contiguous to the above mentioned partitions

14—15 I provide a U-shaped (in cross section) vertically arranged housing 18 opening forwardly and its open side adapted to receive a strip of glass 19 for a purpose to be described. At either side of said strip the front of the cabinet has a large glazed panel 20 extending down to the floor 12 and in front of the lower space or compartment 10 a single glazed panel 21 extends across the entire frame. Corresponding upper and lower panels 22—23, respectively, are provided in the ends of the cabinet and the rear wall 24 thereof may be solid except for a hinged door 24^a permitting access to the lower chamber 10.

On the bottom 11 of the lower chamber 10 I secure a number of electric light sockets 25 in which are inserted electric bulbs 26 all operatively connected to an electric circuit (not shown) and controlled from a switch box 27 in the rear wall (see Figs. 4 and 8) by a switch button 28, current running into said switch box through a cable 29 from any suitable electric source.

As shown in Figs. 2 and 4, one electric socket is placed directly under the housing 18 and a bulb 26^a of the elongated type extends upwardly into said housing for the purpose of illuminating the housing 18 and throwing light out therefrom through the glass 19 which may have any desired lettering on it, such as "Fresh hot peanuts" (see Fig. 2).

Other bulbs 26 may be arranged linearly 90 below and between the partitions, the heat from said bulbs rising between said partitions and circulating into the upper compartments of the cabinet through perforations 30 provided in said partitions (see 95 Figs. 3 and 4).

In Figs. 1 to 4 inclusive, I have shown two inverted L-shaped pipes 31, one in each compartment, and having its lower end terminating over and partly covering a bulb 26, 100 its horizontal portion terminating at and registering with an aperture in the adjacent wall 14 or 15, thus conducting heat from the bulb vertically and horizontally through the compartment to the space between the 105 walls 14—15 and thence the hot air circulates into the upper portion of both compartments through the perforations 30. The partitions or wall members 14—15 may be suitably secured as at 32 to the rear wall of 110 the cabinet and their lower edges may be flared as 14^a—15^a (Figs. 2 and 5) in the

compartment 10 to more readily catch and conduct the heat upwardly from the center bulbs 26. 26^b in Fig. 4 designates the location of extra bulbs which may be used to create heat under the perforated plate 12 at points remote from the heating means already described.

In the modification, Figs. 6 and 8, the cabinet has only a single upper compartment in which the two heat conducting pipes 31^a are merely elbows, the horizontal ends of which are connected by a pipe 33 perforated as at 34 to spread the heat conducted from the bulbs 26 into the single large compartment. There may be another heat conducting pipe 33^x crossing the pipe 33 (see Fig. 8).

Referring particularly to Figs. 2, 3, 5 and 6 it will be readily seen that the light from the bulbs is thrown out through the glazed side panels 23 and the front panel 21 inclosing the lower compartment on three sides, whereas the heat from the bulbs circulates upwardly into the upper compartments in the various directions already described. The glass of said panels 21-23 may be of any bright color (indicated red) except for fields of clear glass forming suitable words, as shown in Fig. 7.

In the use of my device, it will first be understood that store-keepers, and vendors of peanuts and the like, usually get the nuts already roasted and ready to sell. Peanuts, however, are more desirable and palatable to the consumer if they can be purchased while hot. My device is therefore particularly desirable for a dealer who sells direct to the consumers. A dealer having one of my improved cabinets merely dumps his supply of roasted peanuts into the large upper compartment or compartments, which may also be called magazines, and shuts the lids 17 tight, then closes the circuit at switch 28. The heat from the bulbs then circulates upwardly through the entire mass of peanuts in the various directions already described and the light from the bulbs illuminates the lettered panels. A thermostatic control (not shown) may be installed to keep the peanuts heated to any predetermined temperature.

What I claim is:

1. A device of the class described comprising an upright, comparatively air tight cabinet with glazed sides and having a large upper chamber adapted to be used as a magazine for peanuts and the like, and a lower chamber and means therein for simultaneously illuminating the cabinet and providing heat for warming the contents of the magazine and means for distributing the heat in the magazine, said illuminating and heating means comprising a number of electric lights mounted in the lower chamber, a circuit connecting the lights, and means for opening and closing the circuit. 60

2. The structure specified in claim 1, said magazine provided with a perforated bottom having a number of large apertures each vertically above one of the lights in the lower chamber, a heat conducting pipe mounted in each of said apertures and extending vertically therefrom into the magazine and thence horizontally through the magazine for the purpose described. 70

3. The structure specified in claim 1, said magazine having a vertical partition comprising two spaced wall members extending from the under side of the cover of the cabinet downwardly into the heating chamber, said walls having apertures in their upper portions, the lower portions of said walls within the heating chamber being spread to catch heat from the heating means, and the latter comprising a number of electric lights placed in said chamber. 80

4. The structure specified in claim 3, said partitions having also a number of large apertures, heat conducting L-shaped tubes having each one end of its horizontal portion registering with one of said large apertures and its vertical portion extended downwardly through the magazine floor into the heating chamber for the purpose described. 90

5. The structure specified in claim 1, and a vertically disposed housing or duct in the front wall of the cabinet and having a glazed front panel adapted to be illuminated by one of the electric bulbs mounted in the lower or heating chamber. 95

In testimony whereof I affix my signature.
SAMUEL S. FISHER.
